UNITED STATES PATENT OFFICE

SAMUEL TURNER, OF BERKS, ENGLAND, ASSIGNOR TO RADIO CORPORATION OF AMERICA, A CORPORATION OF DELAWARE

HIGH-FREQUENCY SYSTEM

Application filed November 26, 1924, Serial No. 752,428, and in Great Britain December 20, 1923.

This invention relates to high frequency telephony whether wireless or wired wireless. In the case of two telephone exchanges connected by a high frequency trunk it is desirable that the operators shall be able by the usual operations, that is, the operations that would be employed if the stations were connected by an ordinary telephone trunk, to start and stop the generation of the carrier waves and to give the calling and clearing signals and that false calls shall not be given.

The object of this invention is to provide a system having these desiderata even when the high frequency station is at a distance from the exchange.

According to this invention the generation of the carrier wave is started by a relay, hereinafter called the starting relay, the circuit of which is controlled by a relay, hereinafter called the control relay, the circuit of which is in turn under the control of a slow release relay which is energized on the receipt of waves from the distant station.

The invention is illustrated by the accompanying diagram, in which Fig. 1 diagrammatically illustrates a telephone exchange according to my invention and Fig. 2 diagrammatically illustrates a system comprising two such telephone exchanges. Referring more particularly to Fig. 1 T represents a wireless transmitting station and R a wireless receiving station. The generation at T of the carrier wave is controlled by a relay E which is operated by a starting relay S R at a telephone exchange, the circuit of this relay S R being under the control of a relay C. The receipt of the carrier wave from a distant station at R causes a receiving relay A to energize and thus to connect R to the exchange through a cable, not shown.

When an operator at an exchange Y wishes to call an exchange Z she inserts a plug 1 into a jack 2 and through the sleeve of her jack energizes relay C O. Relay C O energizing completes the circuit of starting relay S R through the back contact of control relay C and also prepares the circuit of a slow release relay D. S R on energizing completes through the cable the circuit of relay E which on energizing causes the carrier wave to be

transmitted. This carrier wave is received at the wireless station of exchange Z and actuates relay A which completes a circuit through the cable connecting that station to exchange Z and through call relay B in the exchange. This relay on energizing completes the circuit of a calling lamp C L. The operator at exchange Z plugs into a jack and causes the emission of a carrier wave from the transmitting aerial of exchange Z in exactly the same way as the emission of the wave from exchange Y was effected.

The receipt of the waves at exchange Y causes relay B to be actuated but inasmuch as the circuit of the slow release relay D had been prepared as above stated this relay energizes and breaks the circuit of lamp C L so that no calling signal is given at exchange Y.

Conversation can now take place between the two operators or between subscribers to whom they may extend the connection.

At the end of the conversation one of the operators, we will suppose the operator at exchange Z removes her plug from its jack, C O and S R therefore release, and consequently the emission of the carrier wave from the station at Z is stopped. The circuit of relay D is therefore broken at exchange Y, but its armature still remains for a moment on its front contact and thus the circuit of relay C is completed. This relay on becoming energized completes a circuit through the clearing signal c l of exchange Y, breaks the circuit of relay S R and completes a locking circuit for itself, so that when the armature of relay D drops back control relay C remains energized and relay S R remains de-energized. Thus after a short interval of time from the removal of the plug at exchange Z, the transmitter at exchange Y has been automatically disconnected, but it will be evident that during this interval of time, the transmitter at Y will be sending out waves to exchange Z. But this will not cause a false call as D being slow to release has locked itself in a circuit through a back contact of C O and a front contact of B. Thus the withdrawal of the plug at either exchange automatically shuts down both the wireless transmitters and gives the clearing signal at the other exchange.

Should the operator at station Y fail to remove her plug, the carrier wave is not generated and therefore no false call will be given at exchange Z. As soon as the operator at exchange Y removes her plug everything is restored to normal and she can therefore initiate a fresh call by reinserting her plug into its jack.

Thus suppose that after a conversation the operator at Y clears first, but is about to call again before the Z operator removes her plug. On receipt of the clear signal and just before the second call from Y the conditions at Z will be plugged in, *call* lighted, CO and C operated, A, B, D, S R, E and CL disconnected. When Y calls her carrier wave will operate relays A and B at exchange Z and so the eventual removal of the plug by the Z operator will release CO and C and the circuit of CL will be completed.

It is obvious that the relays A and B can be arranged so as to be operated only on the receipt of a modulated signal instead of on receipt of a carrier wave, as previously described.

The arrangement described above can be employed in any type of telephone exchange.

Having described my invention what I claim is:—

1. In a high frequency duplex telephone installation, the combination of a telephone exchange, transmitting and receiving stations in connection therewith, a starting relay at the exchange whereby the transmitter is set in action, a control relay controlling the circuit of the starting relay, and a slow release relay energized on the receipt at the receiving station of oscillations from a distant station and controlling the circuit of the control relay.

2. A telephone system comprising a pair of telephone stations and a duplex radio circuit therebetween, said telephone stations comprising respectively a transmitting device, a receiving device, a starting relay controlling said transmitting device, a call relay operated by said receiving device, a control relay for breaking said starting relay when said call relay is broken, a call lamp associated with said call relay and a clearing lamp associated with said control relay whereby said call lamp is lighted when said call relay is first energized and said clearing lamp is lighted when said control relay is energized.

3. A telephone system comprising a pair of telephone stations and a duplex radio circuit therebetween, said telephone stations comprising respectively a transmitting device, a receiving device, a starting relay circuit controlling said transmitting device, a relay circuit for operating said starting relay circuit, manually operable means for completing said last named circuit, a call relay circuit operated by said receiving device, a calling lamp circuit adapted to be completed

when said call relay circuit is first completed, a slow release relay circuit energized when said call relay circuit and said starting relay circuit are completed, and a control relay circuit for said starting relay circuit adapted to be completed by the breaking of said call relay circuit and before said slow release relay operates, said control relay acting to complete a locking circuit for itself and to break said starting relay circuit.

4. A telephone system comprising a pair of telephone stations and a duplex radio circuit therebetween, said telephone stations comprising respectively a transmitting device, a receiving device, a starting relay for controlling said transmitting device, a control relay for breaking said starting relay, a call relay operated by said receiving device, and a slow release relay energized when said call relay and said control relay are completed, said control relay being energized by the breaking of said call relay through the slow action of said slow release relay whereby said starting relay is broken.

5. A telephone system comprising a pair of telephone stations and a duplex radio circuit therebetween, said telephone stations comprising respectively a transmitting device, a receiving device, a starting relay for controlling said transmitting device, a control relay for breaking said starting relay, a call relay adapted to be completed by said receiving device, a slow acting relay adapted to be broken when said call relay is broken and a lamp adapted to be lighted when said call relay is broken, said control relay being energized by the breaking of said call relay due to the slow action of said slow acting relay, and said control relay acting upon energization to break said starting relay and to complete the circuit of said lamp.
